MOUNTING FOR MAGNETIC CORES

Edgar O. Sprude, Overbrook, Pa., assignor to Burroughs Corporation, Detroit, Mich., a corporation of Michigan

Filed June 6, 1956, Ser. No. 589,623

3 Claims. (Cl. 340—174)

The present invention relates to support structure and more particularly to structure for mounting components on boards or metal chassis.

In the mounting of such components and illustratively the mounting of bistable magnetic cores, one practice heretofore has been to prepare terminal panels or boards, of Bakelite or other insulating material, with serrated margins forming teeth or turrets, each of which is drilled with a core locating hole. Blank core bobbins are cemented in place over the respective holes whereupon windings are put on the bobbins by manually threading the wires through the core hole and the drilled hole in the board. This serrated construction provides sufficient clearance for the hand winding of the bobbins.

An important object of the present invention is to provide a novel support structure for mounting components.

Another important object is to provide a support structure wherein the time required for assembly of components therewith is considerably reduced as compared to former procedures.

Another important object is to provide a support structure for magnetic cores making it possible to use pre-wound toroid cores.

A further object is to provide a toroid core assembly wherein the cementing of cores to a terminal board is eliminated.

A further object is to provide a core mounting which makes it possible to assemble the cores on a metal chassis.

A further object is to provide a novel support structure for mounting a component in the plane of a mounting board.

A still further object is to provide a core mounting wherein an effective cushioning or shock-absorbing condition is made possible.

Various other objects, advantages and meritorious features of the invention will become more fully apparent from the following specification, appended claims and accompanying drawings wherein:

Fig. 1 is a perspective view of a support unit embodying one form of the present invention shown mounted on a plastic board or metal chassis;

Fig. 2 is a section view on a larger scale taken on line 2—2 of Fig. 1;

Fig. 3 is a perspective view of one form of toroidal core to be mounted;

Fig. 4 is a plan view of a chassis with a plurality of units mounted on a board and showing the improved close spacing of the units, such showing being substantially of actual size;

Fig. 5 is a section view on line 5—5 of Fig. 4 and showing a core being inserted;

Fig. 6 is a section view like Fig. 5 showing a core as finally mounted;

Fig. 7 is a perspective view of a modified form of the invention and showing a core in place;

Fig. 8 is a perspective view of another modification of the invention;

2

Fig. 9 is a side elevation view, in part section, of a further modification of the invention; and

Fig. 10 is a section on line 10—10 of Fig. 9.

Referring to Figs. 1 to 5 of the drawings one support unit in accordance with the present invention is in the form of a grommet-like housing 10 is shown assembled on a board or chassis 11 having unit receiving holes 12 prepared therein for spacing a plurality of units side by side in close proximity. This close spacing should be particularly noted because heretofore it has been necessary to provide a serrated margin of the board to space the drilled holes sufficiently to permit winding of the cores when assembled in the respective holes. This heretofore wide spacing is no longer required because the present mounting makes it possible to use pre-wound cores. The unit 10 is formed of rubber or other non-conducting resilient material molded or formed as a relatively shallow body having an internal cylindrical compartment 13 dimensioned to receive a toroidal core component 14 such as shown in Fig. 3. The upper face of the unit 10 has an aperture 15 communicating with the compartment 13 and serving, when the body is distorted, to admit the core 14. An opening 16 may also be provided in the bottom face of the unit 10 for the passage of core lead wires when such are needed in addition to the core leads traversing the aperture 15.

The opposite ends of the unit 10 are respectively bifurcated to provide end slots 17 and 18 of a width to snugly receive and grip opposite board margins of a board hole 12. Opposite sides of the unit are respectively cut away to leave two aligned plane edges 20 and 21 which materially reduce the overall width of the unit whereby a maximum number of units can be mounted in close spaced relation. Also it will be observed that the bottom wall 22 of the slots 17 and 18 is complementary to the shape of board holes and dimensioned to seat snugly therein. The magnetic cores components 14 are each in the form of a toroid of the order of one quarter of an inch in diameter and are preformed by machine or hand winding ready for mounting in a unit 10. This stated size is not to be taken as a limitation because various sizes and correspondingly dimensioned units are within the scope of the invention. The core components may be designed for memory storage in computers and the like and for this purpose may assume one or the other of two stable states depending upon the current excitation of the windings therewound.

In order to mount a unit 10 on a board 11 the unit body is compressed transversely to permit one bifurcated end to enter the selected hole 12 and be pushed laterally to seat the slot 17 about the hole margin at one side, after which the opposite bifurcated end is transversely distorted and forced into position with the opposite hole margin seated in the slot 18. The mounting is now in place to receive a core 14 which can then be pushed through the hole 15 by inwardly flexing the relatively thin annular portion of the body which encircles the hole 15. The core 14 is shown in Fig. 5 being pressed through the hole 15. As soon as the upper core flange passes inwardly beyond the inturned hole margin this latter snaps back over the top of the core to hold the core properly housed. It is apparent that in this embodiment of the invention the core component is mounted in the plane of the board 11 thus reducing the overall thickness of the chassis assembly and aiding in the mounting of such assemblies close together.

In the modified form of the invention shown in Fig. 7 the unit body 23 of rubber or other resilient material and of generally rectangular shape having a length greater than the diameter of a hole 12 in which the body is to be mounted. Opposite ends of the body are bifurcated

to form slots 24 and 25 to respectively seat opposite margins of the hole 12. In this form the body 23 is formed with a transverse open sided compartment 26 arranged and dimensioned to receive a core 14 through the side opening with its axis normal to the plane of the board which is to hold the unit. The top and bottom faces of the unit 23 are respectively extended to provide a protective thickness for the top and bottom of the core 14. Preferably the extended portion of the top of the unit has a relatively small aperture 27 coaxial with the core for the passage of core leads. This form of the invention can be assembled on a board by distorting the bifurcated ends to enter a hole 12 as explained in connection with the unit of Fig. 1.

Referring to Fig. 8 of the drawings, another form of the invention is shown wherein the unit 30 is in the form of a resilient relatively thin flat plate having a T-shaped extension 31 on its bottom margin forming oppositely aligned slots 32 and 33 for respectively seating opposite margins of a hole 12 in the panel 11. The shank portion of the extension 31 is complementally contoured to seat about the hole 12.

For mounting a core 14, a transverse through hole 34 is provided in the body dimensioned to snugly receive the core 14 and also provide means for anchoring the core 14. In this instance the anchoring means is an inwardly disposed nose 35 molded in the relatively thin flexible top which bounds the hole 34. In assembling this type of unit the extension 31 is distorted and pushed through a board hole 12 until its head snaps about the hole margin which then seats in the slots 32 and 33. When thus fixed in place the body rises perpendicular to the board ready to receive a core, which can then be pressed laterally into the hole 34 forcing the flexible top to distort so that the nose 35 rides over the top of the core to snap into coaxial holding position within the bore of the core. In this form of the invention the wound core can be located either before or after the unit is attached to the board.

In the form of the invention shown in Figs. 9 and 10, the resilient body is in the form of a flat shank 36 terminating at one end in a head 37 and at the opposite end in a base 38 for mounting the body upon a terminal board 11 with a provided base receiving hole 12. The shank 37 has a width less than the diameter of the bore of a core 14, and a length between the head 37 and the base 38 substantially equal to the length of the core 14 whereby the core is anchored in assembled condition. The head 37 is generally convex to form relatively thin portions capable of being flexed to pass through the core of a core under distorting pressure, and emerge as a self-restored retainer abutting one end of the core. The base 38 is formed with two opposite laterally disposed bifurcations 40 respectively forming slots 41 and 42, each of which in assembled condition seats a margin of the board 11. As finally positioned the core 14 coaxially encircles the shank 36 and is held firmly between the head 37 and the base 38.

It will now be apparent that the invention provides a novel unitary support structure for mounting components. In particular it provides a support structure affording easy and economical assembly of magnetic cores on a mounting panel, while at the same time eliminating the aforesaid tedious hand-winding and cementing operations. Further, the components are supported by resilient units of rubber or the like which afford effective cushioning and shock-absorbing. Since the mounting body is of insulating material it is now possible to mount the units upon a metal chassis. Also by reason of the now possible close spacing of units in side to side relation more units can be mounted upon a terminal board than has been possible heretofore.

What is claimed is:

1. In a memory storage assembly for computers and the like comprising in combination, a panel having a plurality of spaced openings therein, a plurality of housings mounted in said openings, each housing being of resilient insulating material and having a compartment adapted to substantially enclose a memory storage unit therein, said housing consisting of an elongated tubular body portion and inwardly extending top and bottom end portions contiguous therewith for substantially closing the ends of said tubular portion, each end portion including an aperture axially aligned with the tubular body portion and being of a smaller diameter than said tubular body portion, a magnetic memory unit of larger diameter than said apertures received in said compartment, electrical windings around said unit and extending therefrom through one of said apertures, and grooved flanges extending outwardly from the tubular body portion and centered axially therewith, said flanges being received in an opening of said panel to mount said housing therein.
2. In a memory storage assembly for computers and the like comprising in combination, a panel having an opening therein, a housing mounted in said opening, the housing being of resilient insulating material and having a compartment adapted to substantially enclose a memory storage unit therein, the housing consisting of an elongated tubular body portion and inwardly extending top and bottom end portions contiguous therewith for substantially closing the ends of said tubular portion, each end portion including an aperture axially aligned with the tubular body portion and being of a smaller diameter than said tubular body portion, a magnetic memory unit of larger diameter than said apertures received in said compartment, electrical windings around said unit and extending therefrom through one of said apertures, and grooved flanges extending outwardly from the tubular body portion and centered axially therewith, said flanges being received in the opening of said panel to mount said housing therein.
3. In a memory storage assembly for computers and the like comprising in combination, a housing adapted to be mounted in an opening in a panel, the housing being of resilient insulating material and having a compartment adapted to substantially enclose a memory storage unit therein, the housing consisting of an elongated tubular body portion and inwardly extending top and bottom end portions contiguous therewith for substantially closing the ends of said tubular portion, each end portion including an aperture axially aligned with the tubular body portion and being of a smaller diameter than said tubular body portion, a magnetic memory unit of larger diameter than said apertures received in said compartment, electrical windings around said unit and extending therefrom through one of said apertures, and grooved flanges extending outwardly from the tubular body portion and centered axially therewith, said flanges being received in the opening of said panel to mount said housing therein.
